Patented July 30, 1974

232,206

MEDICATION CABINET

David B. Geddis, Somerville, N.J., assignor to Johnson & Johnson

Filed Aug. 19, 1971, Ser. No. 173,343

Term of patent 14 years

U.S. Cl. D6—158 Int. Cl. D6—04

FIG. 2.

FIG. 5.

FIG. 1 is a front perspective view of a medication cabinet showing my design;

FIG. 2 is a plan view;

FIG. 3 is a view in front elevational;

FIG. 4 is a perspective view showing the side opposite that illustrated in FIG. 1 and showing the drawer removed; and

FIG. 5 is a bottom perspective of the medication cabinet.

I claim:

The ornamental design for a medication cabinet, as shown and described.

No references cited.
